UNITED STATES PATENT OFFICE.

JOSEPH T. COMMOSS, OF BROOKLYN, NEW YORK.

SMOKE-RING TOY.

SPECIFICATION forming part of Letters Patent No. 515,464, dated February 27, 1894.

Application filed February 24, 1893. Serial No. 463,538. (No model.)

To all whom it may concern:

Be it known that I, JOSEPH T. COMMOSS, a citizen of the United States, residing in the city of Brooklyn, county of Kings, and State 5 of New York, have invented certain new and useful Improvements in Smoke-Ring Toys, of which the following is a specification.

The object of my invention is to produce a device in the nature of a toy, which shall be 10 adapted to receive a charge of smoke and permit it to be expelled therefrom in puffs, each assuming the form of a ring. This object I have attained by the novel features hereinafter set forth and claimed, and illustrated in the accompanying drawings, in 15 which—

Figure I represents a side view of a toy embodying my invention, as it appears when 20 fully distended. Fig. II represents a longitudinal section thereof. Fig. III represents a side view thereof, as it appears when folded. Fig. IV represents a top view thereof, with the cap partially removed.

Similar letters of reference indicate similar 25 parts.

The letters A, B, indicate two disks, and C, a web or jacket connecting the disks, forming the principal features of the toy. The disks A, B, are composed of paste board or 30 other like rigid material, one (A) being usually covered with thin sheet metal, as at A'; while the jacket C, is composed of paper or other flexible material, to render it capable of folding or collapsing, causing the disks and 35 jacket, jointly, to act as a bellows. When the flexible jacket C, is of paper, it is preferably laid in folds, as shown, and glued to the disks.

The central portion of the sheet metal A' 40 of the top disk A, is raised, forming a dome D, which is perforated with a central hole e, and upon which there is hinged to said disk a central cap F, as by a pivot g, in such a manner as to adapt this cap to overlap the 45 hole of the disk, or dome. The cap F, usually has a finger piece i, to facilitate its adjustment; and it is perforated with a central hole s, which is smaller in diameter than the hole e of the dome. Both the holes e, s, are

approximately round in shape; and when the 50 toy is to be applied to use, the perforated cap F, is set over the hole e, the pocket C, is distended, and taking hold of the disk A, with the fingers of the left hand, a charge of smoke is blown into the body of the toy 55 through the hole s of the cap. The cap F, is then removed from the hole e, and the bottom disk B, is gently and repeatedly tapped with one of the fingers of the right hand, whereby the smoke is expelled through the 60 hole e, in puffs, each of which assumes the form of a ring as it emerges from said hole.

It will be noticed that by making the hole s, of the cap, of relatively small size, it has a tendency to confine the smoke in the toy 65 until the main hole e, is exposed; but it is evident that the cap hole s, may also be used for creating the desired smoke - rings, by leaving the cap in normal position, thus permitting a variation in the diameter of the 70 rings. The effect of the dome D, is to concentrate or deflect the smoke toward the middle of the disk A, insuring its uniform expulsion through the hole e, so as to produce comparatively solid smoke rings; and 75 when the cap F, is left in position on the dome for creating the desired rings, the cap tends to further concentrate the escaping smoke.

In some cases either or both of the disks 80 A, B, may be utilized for displaying an advertisement.

When the toy is not in use, the jacket C, may be folded as shown in Fig. III, bringing the whole into a comparatively small compass, for convenience of carriage, as in the 85 pocket.

What I claim as new, and desire to secure by Letters Patent, is—

1. A smoke-ring toy comprising the two 90 rigid disks, one perforated with a central hole, the central cap hinged to the perforated disk to overlap its hole and perforated with a central hole smaller than the hole of the disk, and the flexible jacket connecting the disks, 95 forming a bellows, substantially as and for the purpose herein described.

2. A smoke-ring toy comprising the two

rigid disks, one with a central dome perforated with a central hole, the central cap hinged to the perforated disk upon its said dome, to overlap the hole therein, and perforated with a central hole smaller than the hole of the dome, and the flexible jacket connecting the disks, forming a bellows, all sub-

stantially as and for the purpose herein described.

JOSEPH T. COMMOSS.
